UNITED STATES PATENT OFFICE.

EDWARD POSSON, OF CHICAGO, ILLINOIS.

REFRIGERATOR-CAR CONSTRUCTION.

1,388,600.

Specification of Letters Patent. Patented Aug. 23, 1921.

Application filed December 19, 1917. Serial No. 207,833.

To all whom it may concern:

Be it known that I, EDWARD POSSON, a citizen of the United States, residing at Chicago, in the county of Cook and State 5 of Illinois, have invented certain new and useful Improvements in Refrigerator-Car Construction, of which the following is a specification.

This invention relates to improvements in 10 refrigerator car construction, and to a new article of manufacture for use as an insulating material in the construction of the walls and floors of the car.

Some of the best insulating materials, such 15 as hair felt, for instance, do not in themselves possess sufficient stiffness to be self-supporting when used in the side wall construction of cars, and the disintegrating effect of vibration soon causes the insulating 20 material to sag and break down. The principal purpose of the present invention is to provide an improved composite insulator having better heat-insulating qualities than felt hair and other similar materials, and in 25 which such materials are given sufficient strength by reinforcement to enable them to sustain their own weight when mounted vertically. In my improved insulator a plurality of layers of cellular or porous insulating material having considerable flexibility, such as hair felt and the like, are 30 united and cemented to layers of relatively stiff material, preferably having insulating qualities, so that a composite insulating 35 structure is formed, having greater heat-insulating qualities than its principal constituent taken alone, without perforating the heat-insulating material, or otherwise providing air spaces through which heat might 40 escape.

The insulating material used to insulate refrigerator cars beneath the floor and the side and end walls for short distances upwardly from the floor is liable to become 45 injured by moisture, and its effectiveness thereby destroyed, unless means be taken to render the insulating material moisture-proof, and the advantage of a waterproof material may be easily obtained by using 50 the present invention, in which the insulating structure after fabrication has its edges, or the entire body thereof, dipped in a bath of hot asphalt, or similar substance, to give it a waterproof coating and to impregnate

the open edges thereof with waterproofing 55 material, so that the sections of insulation liable to come into contact with moisture are maintained in a dry state. A further feature of the invention is the combination of my improved insulator with novel means 60 for securing the same in the car structure.

These and other objects and features of the invention will be set forth more fully in the following specification, taken in connection with the accompanying drawings, in 65 which several embodiments of the invention are illustrated.

In the drawings—

Figure 1 is a perspective view of a portion of a refrigerator car with parts thereof 70 broken away, and showing a section taken transversely through the car;

Fig. 2 shows a plan view of a section of insulating material used in the construction of the car illustrated in Fig. 1;

Fig. 3 shows a plan view of a section of insulating material of different size;

Fig. 4 shows an enlarged perspective view of one form of my improved insulating composition, with a portion thereof cut away to 80 illustrate the interior construction;

Fig. 5 is a view similar to Fig. 4, showing a modified construction of the composite insulating material;

Fig. 6 is an enlarged perspective view, 85 showing a further embodiment of the invention;

Fig. 7 is an enlarged perspective view, showing still another embodiment of the invention;

Fig. 8 is an enlarged perspective view, showing a fifth modified form of the invention;

Fig. 9 is a vertical sectional view through the side wall of the car, showing my improved method of employing the insulator in car construction;

Fig. 10 is a view similar to Fig. 9, showing a modified form of construction; and

Fig. 11 is a section taken transversely 100 through a tank car, showing the adaptation of my improved insulator to cars of that type.

In the accompanying drawings the refrigerator car is shown as comprising a plurality of longitudinal floor sills 15, which are spaced apart as illustrated by transverse sills or spacers 16, and which are adapted to

support the floor boards 17 of the car. The side walls 18 extend upwardly from the outer longitudinal sills 15, being united by end walls 19 and arranged to support the car 5 roof 20. The side walls comprise the horizontally extending belt rails 21, which are spaced apart vertically, as shown, and are inclosed by the inside sheathing 22 and the outside sheathing 23, so that compartments 10 are formed which are adapted to receive the heat-insulating material as will be herein-after described. The side plates 25, along the upper edges of the car wall, support the outer edges of the roof 20, and the inner 15 portions of the roof are carried by the longitudinal purlins 26, which are spaced apart to form compartments for receiving the heat-insulating material.

The various compartments in the floor, 20 walls, and roof of the car, above referred to, are adapted to be substantially filled by my composite heat-insulating material, which may be constructed, as illustrated in Fig. 4, of two or more layers 30 of loose 25 flexible material, such as hair felt pressed into the form of layers or sheets, and these sheets of hair felt or the like are united by a sheet 31 of material having considerable stiffness, and preferably of heat-insulating qualities, such as wool felt paper, 30 which is cemented to the layers 30 by a suitable material, preferably sodium silicate. Other stiffening layers 32, preferably of similar material, are cemented to the outer 35 surfaces of the outer layers of hair felt or the like, and when one layer only of the loose flexible material is employed the outer surfaces thereof only are covered with the stiffening material cemented thereto. The 40 uncovered edges 33 of the sheets 30, which are not covered by the stiffening material 31-32, would ordinarily permit moisture to penetrate the body of the layers of insulating material, but this defect is overcome 45 by dipping the edges of the insulator in suitable waterproofing compounds, such as hot asphalt or the like, so that the edges 33 of the layers 30 and the edges of the sheets 32 are coated and impregnated with a layer 50 34 adapted to prevent moisture from entering the insulator. The dipping of the layers into the heat-insulating material is preferably done after fabrication of the layers into a composite structure, and, if desired, 55 the entire insulating structure may be dipped in the insulating and waterproofing compound to give it a complete waterproof coating 35, as illustrated in Fig. 5.

The insulating material as described in 60 connection with Fig. 4 is made up into blocks or sections 36 and 37, as illustrated in Figs. 2 and 3, respectively, and these sections are adapted to be inserted between the longitudinal sills, for instance, of the 65 car floor. The sections 36, which are used

between the sills 15, preferably include a relatively large number of layers of the insulating material cemented together in the manner described, and having their edges dipped to provide the coating 34, or having the entire section dipped to form a coating 35. The layers of material used in the floor construction are preferably of the same size, so that their edges abut against the vertical surfaces of the longitudinal 70 and transverse sills of the floor, and the insulating sections are held against vertical displacement by the longitudinal and transverse cleats 38, which are secured to the sills. In the construction of the side walls 75 the main belt rails 21 are preferably of considerable width vertically, and have secured to their outer sides longitudinally extending ribs or cleats 40 of less width than the rails. In forming the insulating sections the outer layer 30^a of the material 30 is preferably arranged to overlap the upper and lower edges of the inner layer 30^b, so that while the inner layers of material fit between and abut against the strips 40, the outer layers overlap the strips, and these outer layers 30^a of adjacent insulating sections abut against each other, so that the insulating material extends continuously 80 through the side walls from the roof to the floor of the car. It will be understood that the vertical and transverse frame members are constructed similarly to the belt rails and are overlapped by the outer layers of insulating material, so that each sectional 85 insulator has the form illustrated in Figs. 2 and 3. Cleats 41 are then secured over the overlapping edges of the layers of the insulating material, and the outside sheathing 23 is secured to these cleats. The side plates 90 25 and the longitudinal sills 15 at the edges of the car are notched or cut away longitudinally, as shown at 42 and 43, respectively; so that the edges of the sections of insulating material overlap and fit into these 95 notches in the same manner that the sections fit into the belt rails 21 and longitudinal strips 40. The sectional insulators in the side walls beneath the lower belt rails 100 are provided with waterproof coatings. 105

In the roof of the car the purlins 26 preferably have a substantially T-shaped construction, whereby longitudinal shoulders 26^a are formed to engage and support the longitudinal edges of the insulating sections 110 36^a. In the embodiment illustrated these sections have three layers of the insulating material, and the uppermost layer thereof is adapted to overlap the purlins 26 and to engage suitable longitudinal notches in the 115 side plates 25, so that the upper layers 30^a of the insulating material abut against each other, while the edges of the lower layers abut against the purlins and the side plates. Longitudinal strips 44 are secured over the 120 125 130

overlapping edges of the sheets 30^a, and the entire construction so formed is covered by the outer roof boards 45 and the inner roof or ceiling boards 46. The method of uniting the edges of the insulating sections with the car framework above described may be more clearly understood by reference to the enlarged sectional view shown in Fig. 9.

10 In Fig. 10 there is illustrated a modified form of construction, in which the belt rail 21^a has a longitudinal strip 40^a secured thereto and projecting therefrom a distance corresponding to the thickness of the insulating sections 47, the layers of which are the same size and adapted to abut against the strip 40, where they are held in position by a cleat 48, of larger dimensions, which overlaps the adjacent edges of the insulating sections. This insulating section is inclosed by the inner sheathing 22^a and the outer sheathing 23^a as in the construction previously described. In either form of construction the sections of insulating material are held firmly in place, and substantially air-tight joints are formed, so that air cannot pass from the interior of the car to the outside thereof.

15 In Fig. 6 I have illustrated a modified construction of the composite heat insulator, in which two layers 50 of heat insulating material, such as body hair felt or the like, are cemented together and reinforced by an intervening layer 51 of some material such as 20 magnesium, which not only unites the outer layers of felt but imparts sufficient stiffness to them to enable them to sustain their own weight.

25 In Fig. 7 a further embodiment of the invention is illustrated, in which two outer layers 52 of flax-board, or the like, are cemented to an intervening layer 53 of hair felt to impart stiffness to the latter and to render the entire structure sufficiently stiff 30 to support its own weight when placed vertically as in the side wall construction of a car.

35 In Fig. 8 a fifth embodiment of the invention is illustrated, in which the outer layers 54 of hair felt or the like are united by an intervening cementing layer 55 as in the form illustrated in Fig. 6, except that the layer 55 has insulating material mixed with the cement to form a relatively thick layer 40 which not only unites the layers of hair felt but increases the heat-insulating qualities of the entire structure.

45 In Fig. 11 I have illustrated the adaptation of my improved insulating material to 50 tank cars, and the like. The inner metal wall 60 of the tank car is spaced from the outer sheet metal covering 61, and this intervening space is adapted to be filled with heat-insulating material, which may be effectively accomplished by using the present invention in

which the heat insulator is made up in sections 62, each consisting of a plurality of layers 63 of body hair felt, or the like, cemented together along their contacting surfaces 64 and arranged so that the edges 63^a 55 of each innermost layer will underlie and be overlapped by the edges 63^b of the outer layer of insulating material of the adjacent section. The edges of the inner layers are adapted to abut against each other, and the edges of the outer layers are similarly in contact, so that a tight joint is formed between adjacent sections of the insulating material whereby the passage of heat is effectively prevented.

50 While my invention is of particular advantage in the construction of refrigerator cars, it will be seen that it may be put to other uses of the class herein described without departing from the scope of the invention as 55 defined in the appended claims.

I claim:

1. In a refrigerator car, an insulated wall comprising a plurality of sectional heat insulators each comprising a plurality 90 of relatively thick layers of flexible insulating material united and supported by sheets of stiffening material cemented thereto, and a framework for uniting and supporting said sections, some of said layers 95 being arranged to abut against said framework, and other layers being arranged to overlap said framework and abut against each other, whereby a continuous sheet of heat-insulating material is formed throughout the car wall.

2. In a refrigerator car, a plurality of frame members spaced apart to form intervening spaces adapted to receive insulating material, sectional heat insulators fitting into said spaces, said heat insulators each comprising a plurality of layers of insulating material cemented together, some of said layers being of less area than the others, whereby the layers of lesser area 105 abut against the lateral edges of said frame members and the layers of larger area overlap said frame members and abut against each other, and securing means overlapping the edges of said layers of larger area.

3. The combination in a railway car, of an insulated wall comprising a plurality of sectional heat insulators each comprising a plurality of relatively thick contacting layers of flexible heat insulating material, 110 some of said layers of heat insulating material having their edges projecting beyond the edges of the other contacting layers, whereby the joints at the abutting edges of the sections of one layer are displaced from the joints of the contacting layers.

4. In a refrigerator car, a vertical car wall comprising a plurality of sectional heat insulators each comprising a plurality 130

of relatively thick layers of flexible heat insulating material united and supported by contacting sheets of stiffening material, cemented thereto, and a framework for uniting and supporting said sections, some of said layers being arranged to abut against said framework and other layers being arranged to overlap said framework whereby some of the layers of adjacent sectional 10 heat insulators abut against each other and form a continuous sheet of heat insulating material throughout the car wall.

5. In a refrigerator car, a vertical wall comprising a plurality of frame members spaced apart to form intervening spaces 15 adapted to receive heat insulating material, said frame members each being composed of connected strips having different dimensions, the wider strips extending beyond 20 the narrower strips and forming seats, and sectional heat insulators fitting into said

spaces and engaging said seats, said heat insulators being formed of a plurality of layers of heat insulating material cemented together and reinforced by layers of stiffening materials cemented thereto, layers of stiffening material being interposed between layers of heat insulating material, some of said layers of heat insulating material being adapted to engage said seats and abut 25 against said narrower strips, other layers of heat insulating material being of larger area and adapted to overlap said strips whereby said last mentioned layers of adjacent heat insulating sections abut against 30 each other along said frame members.

In testimony whereof I have subscribed my name.

EDWARD POSSON.
